UNITED STATES PATENT OFFICE.

WILLIAM F. ALBRECHT, OF SALT LAKE CITY, UTAH.

FAUCET.

Application filed July 2, 1927. Serial No. 303,152.

This invention relates to a faucet, the general object of the invention being to so form the faucet that the working parts can be removed as a unit, with means for enabling the wearable parts to be renewed whenever necessary, such parts also being reversible so that new portions can be brought into use when other portions have become worn.

A further object of the invention is to so 10 arrange the parts that the valve can be used with a single washer and a single washer engaging member or it can be used with two washers and two washer engaging members, with means for providing the valve head 15 with a reversible washer engaging member which may or may not be provided with a washer.

A still further object of the invention is to provide a metal ring for fitting in the ring 20 washer which engages the seat in the faucet body so as to prevent spreading of the washer, this metal ring being capable of acting as a washer engaging member at all times.

25 A still further object of the invention is to provide means for carrying additional washers and washer engaging members by the faucet, so that they will be at hand when new washers or parts are needed.

30 This invention also consists in certain other features of construction and in the combination and arrangement of the several parts, to be hereinafter fully described, illustrated in the accompanying drawings and 35 specifically pointed out in the appended claims.

In describing my invention in detail, reference will be had to the accompanying drawings wherein like characters denote 40 like or corresponding parts throughout the several views, and in which:

Figure 1 is a sectional view through the improved faucet.

Figure 2 is a similar view but showing the 45 valve head provided with a washer.

Figure 3 is a view similar to Figure 2, but showing the flanged sleeve reversed.

Figure 4 is a sectional view showing the 50 valve head provided with a bi-facial seat and three washers.

Figure 5 is a sectional view similar to Figure 4, but showing the sleeve reversed.

Figure 6 is a view of the barrel.

Figure 7 is a view of the flanged sleeve.

55 Figure 8 is a view of a plug for entirely closing the faucet.

Figure 9 is a fragmentary sectional view showing a slight modification.

Figure 10 is a view of the bi-facial seat.

In these views 1 indicates the body of the 60 faucet which is formed with the seat 2, the body being provided with an enlarged part above the seat which forms a chamber 3 which is in communication with the discharge spout 4 and the upper part of the 65 body is formed with a cylindrical extension 5 having threads thereon to receive the closing cap 6 which carries the packing material 7 to make a tight joint with the valve stem 8. An internally threaded barrel 70

9 is held in the body between the seat and the cap, said barrel having a flange 10 at its upper end which fits in an annular groove formed in the cylindrical part and a fiber 75 washer 11 and a metal washer 12 are placed between the upper end of the barrel and the cap so as to make a watertight joint at this point. The barrel is provided with openings 13 adjacent its lower end so that

water passing into the barrel can pass 80 through said openings into the chamber 3 and escape through the spout 4. The valve head 14 on the inner end of the stem is threaded to engage the threads of the barrel and as the barrel is held against rotary 85

movement in the body, the turning movement of the head and stem will cause the head to move toward or away from the valve seat 2. A washer 15 of ring shape fits in the lower end of the barrel and is adapted 90

to engage the seat 2 when the barrel is in proper position in the faucet, and the head is provided with a recess 16 in its lower end which forms an annular projection 17 which 95 will engage the washer when the head is in lowered position and thus prevent water passing from the inlet of the faucet into the barrel or chamber 3. Thus when the annular projection 17 engages the washer, the faucet is closed, but when the head 14 is

raised, water will flow through the opening in the seat into the barrel through the openings 13 into the chamber 3 and will discharge through the spout 4. As will be seen, the washer 15 remains stationary at all times during the operation of the faucet, but when the barrel is removed the washer is removed with it so that a new washer can be easily put in place when necessary.

100 A sleeve 18 having an annular flange 19 110 thereon is adapted to be placed in the opening in the seat with the flange engaging an

annular recess formed in the seat, the sleeve having a portion extending into the opening formed in the washer 15 and this portion prevents spreading of the washer, and as will be seen, when the faucet is closed the washer is almost entirely surrounded by metal. This washer not only acts as a seat for the valve head but it also prevents water from passing between the seat and the barrel and reaching the chamber 3.

The valve head is provided with a threaded hole 20 which communicates with the recess 6 so that a washer 21 can be placed in the recess and held therein by a screw 22 which engages the threaded hole 20. When this is done, the washer 21 will be engaged by the upper end of the sleeve 18 as the washer 15 is being engaged by the part 17 of the valve head so that this construction provides two washers and two washer engaging members, as shown in Figure 2, thus providing a double joint between the valve head and the seat and insuring against leakage from high pressure systems.

25 As shown, I make the sleeve 18 with the flange 19 closer to one end than the other so that by reversing the sleeve as shown at 18' in Figure 3, the washer 21 will engage the projecting upper end of the sleeve, but the part 17 will not engage the washer 15 so that in this arrangement but a single washer and a single washer engaging member are used.

Figures 4 and 5 show a bi-facial seat 23 attached to the valve head by a long screw 22'. These figures also show a washer 24 placed on each side of the seat with the washer 21 placed in the recess of the valve head, but if desired, the seat can be used 40 without the washers as its annular projecting part, engaging the main washer 15, will act to close the faucet when the head is in lowered position. By having the long end of the sleeve 18 uppermost and using a washer 24 on the lower face of the seat 23, one washer and washer engaging part comes into use when the valve is closed, as shown in Figure 4, but by using the short part of the sleeve, as shown in Figure 5, two washers 45 and two washer engaging parts will come into use when the faucet is closed, as shown in said figure. When one face of the seat 23 becomes worn, it can be reversed so as to bring the new face into use and the washers 50 can also be reversed and when the washer being used has become so worn that it is useless, one of the other washers can be substituted therefor and I may form a chamber 25 in the stem handle 26 to receive extra 55 parts, this chamber being covered by a removable cap 27.

If it is desired to entirely close the faucet to prevent the same from being used, I provide a plug 28 which is to be substituted for 60 the sleeve and which closes the opening in

the seat so that no water will pass from the faucet even though the valve head is in raised position, as the plug is held to its seat when the valve head is raised by the washer 15 and the barrel.

70 Figure 9 shows a flanged sleeve 30 used in place of the sleeve 18, this sleeve preventing spreading of the washer 15, and by making the sleeve long enough to extend slightly above the washer, this sleeve could be used 75 as a seat or washer engaging member.

From the foregoing it will be seen that I have provided a faucet having a removable unit which carries all the working parts and in which the wearable parts are removable 80 so that they can be renewed and some of which are reversible so that when they become worn on one side, they can be reversed to bring the unworn side into use. It will also be seen that the faucet can be easily 85 changed to suit high and low water pressure systems and also that the faucet can have its parts arranged to suit existing conditions in the situation in which it is used.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A faucet of the class described comprising a body having a valve seat therein, an internally threaded barrel removably fitting in the body and having holes therein adjacent its lower end, a washer in the lower end of the barrel engaging the seat, a valve head threaded to engage the threads in the barrel and having a recess in its lower end which forms an annular projection for engaging the washer, a stem connected with the head, a handle on the stem, a cap encircling the stem and removably connected 100 with a part of the body and a sleeve having a part extending into the hole in the washer for preventing spreading of the same.

105 2. A faucet of the class described comprising a body having a valve seat therein, an internally threaded barrel removably fitting in the body and having holes therein adjacent its lower end, a washer in the lower end of the barrel engaging the seat, a valve head threaded to engage the threads in the barrel and having a recess in its lower end which forms an annular projection 110 for engaging the washer, a stem connected with the head, a handle on the stem, a cap encircling the stem and removably connected with a part of the body, a sleeve having a part extending into the hole in the washer for preventing spreading of the same, and a washer fitting in the recess in the head 115 120 125 130

and engaging the upper end of the sleeve when the faucet is closed.

3. A faucet of the class described comprising a body having a seat therein provided with a passage, an internally threaded barrel removably arranged in the body and having holes in its side walls, a ring-shaped washer in the lower end of the barrel and adapted to engage the seat, a reversible sleeve removably fitting in the passage in the valve seat and having a portion passing through the ring-shaped washer, a valve head threaded to engage the threads of the barrel, the lower end of the head having a recess therein which forms an annular projection for engaging the ring-shaped washer when the parts are closed, said head having a threaded hole communicating with the center of the recess so that a washer can be held in the recess by a screw and means for holding the sleeve against movement in the passage but permitting the sleeve to be removed with the barrel and valve parts.
4. A faucet of the class described comprising a body having a seat therein provided with a passage, an internally thread-

ed barrel removably arranged in the body and having holes in its side walls, a ring-shaped washer in the lower end of the barrel and adapted to engage the seat, a reversible sleeve removably fitting in the passage in the valve seat and having a portion passing through the ring-shaped washer, a valve head threaded to engage the threads of the barrel, the lower end of the head having a recess therein which forms an annular projection for engaging the ring-shaped washer when the parts are closed, said head having a threaded hole communicating with the center of the recess so that a washer can be held in the recess by a screw, means for holding the sleeve against movement in the passage but permitting the sleeve to be removed with the barrel and valve parts and a bi-facial valve seat adapted to be fastened to the lower end of the valve head by a screw passing into the threaded hole in the valve head, said screw also being adapted to hold washers on the faces of the seat, if desired.

In testimony whereof I affix my signature.
WILLIAM F. ALBRECHT.
